UNITED STATES PATENT OFFICE.

EDMOND A. FORDYCE, OF BOSTON, MASSACHUSETTS, ASSIGNOR TO LAMSON CONSOLIDATED STORE SERVICE COMPANY, OF NEWARK, NEW JERSEY, A CORPORATION OF NEW JERSEY.

PNEUMATIC-DESPATCH APPARATUS.

No. 873,581.

Specification of Letters Patent.

Patented Dec. 10, 1907.

Application filed July 24, 1905. Serial No. 270,965.

To all whom it may concern:

Be it known that I, EDMOND A. FORDYCE, of Boston, in the county of Suffolk and State of Massachusetts, have invented certain new and useful Improvements in Pneumatic-Despatch Apparatus, of which the following is a specification.

My invention relates to improvements in pneumatic despatch apparatus, and the objects are to connect two separate stations by a single tube for transmitting a carrier in either direction and to supply pneumatic power at one point to be used only during the time a carrier consumes in passing between two stations; further, to arrange for the automatic discontinuance of the power at the terminal after the passage of the carrier.

To carry out my invention, I unite two stations by a single tube with an air pump located preferably near one end of the tube with a suitable motor for operating said pump. Devices are provided for starting and stopping the air pump and for reversing the direction of the air current, so that at one time I can produce an air pressure to transmit the carrier in one direction, and at another time produce a vacuum to transmit the carrier in the opposite direction, and so that when no carriers are in transit in either direction, the pump is stopped and no power is produced. The two stations are connected by electric circuits with a device for starting or stopping the operation of the air pump or for reversing the direction of the air current, with circuit controlling devices at each station to control the circuit and circuit closing devices operated by the passage of the carrier through the tube for automatically returning the parts to their position when the apparatus is not in use.

These and other objects are accomplished by the mechanism hereinafter described and particularly pointed out in the claims.

In the accompanying drawings which illustrate a construction embodying my invention, Figure 1 is a side elevation with parts in section illustrating the passage of a carrier from the left hand terminal to the right hand terminal from which it is about to be discharged. Fig. 2 illustrates the apparatus in its normal position with no carriers being transmitted. Fig. 3 is a side elevation with parts in section and illustrating the passage of the carrier from the right hand terminal to the left hand terminal from

which it is about to be discharged. Fig. 4 is an enlarged detail view illustrating the circuit breaker and contacts as hereinafter fully described.

Like letters of reference refer to like parts throughout the several views.

In Fig. 1 the system is shown in operation despatching a carrier from the left hand terminal B to the right hand terminal A; to despatch a carrier from the terminal B, it is dropped into the terminal at B' and drops by gravity into the tube C operating the lever B² causing the same to move to the position shown in dotted lines Fig. 1, making contact between the wires 1 and 2 causing current to flow from the wire "plus" from the battery through the wire 1 then back through the wire 2 to the magnetic switch C', causing same to become excited and drawing the armature D downward making contact between the contacts E and F; by this time the carrier has passed the lever B² which returns to its normal position, but the magnetic switch C' still remains excited as contact is still maintained between E and F, and current instead of flowing from the "plus" wire through the wires 1 and 2 to excite the magnetic switch, flows from the "plus" wire through the wire 3 to the circuit breaker X in the terminal A to the wire 4 to the contacts E and F through the magnets M and N to the wire 5 to the solenoid E" exciting the same drawing the lever arm H up and throwing arm H' down to place the hood I in connection with the discharge pipe J from the blower J'. Current then flows from the solenoid E" through the wire 6 to the solenoid switch G exciting the same, driving the solenoid core K up and completing the circuit between the contacts O and P, thus completing the circuit for the motor H' through the wire 10 starting the motor which in turn operates the blower J'. Current after exciting the solenoid switch G flows to the "minus" wire completing the circuit. The operation of the blower J causes air to be drawn in through the pipe L through the blower to the pipe J through the hood I and then to the pipe Q to the terminal B; the pressure of air blowing into the terminal B at the point R forces the swinging valve S to close, preventing air from escaping and forcing carriers from the position shown in dotted lines through the tube C to the terminal A. As the carrier passes out of the

2
tube C at the terminal A, the carrier operates the lever B³ operating the circuit breaker and breaking contact between the wires 3 and 4 and demagnetizing the magnets M and N allowing the armature D to move upwards breaking contact between the contacts E and F and demagnetizing the solenoid E'' and solenoid switch G causing the solenoid core K to drop breaking contact between the 10 contacts O and P, thus stopping the motor and stopping the flow of air. Immediately on passage of the carriers out of the terminal A the lever B³ returns to its normal position making contact between the wires 3 and 4 15 and leaving the terminals ready for another carrier.

In Fig. 3 the system is shown in operation despatching carriers from the right hand terminal A to the left hand terminal B. To 20 despatch a carrier from the terminal A it is dropped into the terminal at A' and drops by gravity into the tube C operating the lever B³ causing the same to make contact between the wires 3 and 7 causing current to 25 flow from the wire "plus" through the wire 3 then through the wire 7 to the magnetic switch C² causing the same to become excited and drawing the armature D' downward making contact between the contacts 30 E' and F'. As the carrier passes the lever B³, and said lever returns to its normal position contact is broken between the wires 3 and 7, but the magnets M' and N' remain 35 excited as the current flows from the wire 1 to the circuit breaker in the terminal B through the circuit breaker, through the wire 8 back to the contacts E' and F' through the magnets M' and N' to the wire 9, to the solenoid F² exciting same, drawing 40 the lever H down and placing the hood I in connection with the suction pipe L to the blower J'; current then flows from the solenoid F² through the wire 6 to the solenoid switch G exciting same and drawing the armature K up and completing the circuit between the contacts O and P thus completing 45 the circuit from the motor H' and starting the same, which in turn operates the blower J'. Current after exciting the solenoid switch G flows to the "minus" wire completing 50 the circuit. The operation of the blower J' causes air to be drawn in through the opening A' in the terminal A through the pipe C, through the terminal B, valve S' in the terminal B preventing air making in at this 55 point. Air then passes through the pipe Q to the hood I to the suction pipe L to the blower J', through the blower and is discharged through the pipe J' into the atmosphere. The carrier is drawn through 60 the tube C, through the terminal B and discharges through the valve S'; as the carrier passes out of the tube C at the terminal B it operates the lever B² operating the circuit breaker X', breaking contact between the 65

wires 1 and 8 demagnetizing the magnets M' and N' allowing the armature D' to move upward breaking contact between E' and F', demagnetizing the solenoid F² and solenoid switch G causing the armature K to drop 70 breaking contact between O and P thus stopping the motor and the flow of air. Immediately on the passage of the carrier out of the terminal B, the lever B² returns to its normal position making contact between the 75 wires 1 and 8 and leaving the terminal ready for another carrier.

In Fig. 4 there is shown the circuit breaker and contacts as used in the terminals. The circuit breakers X and X' at opposite ends of the line are identical in construction and operation, so that a description of the circuit breaker X at the right hand end of the line, 80 would clearly apply to that at the left hand end of the line.

The lever B³ is held in its normal position, as shown in Fig. 4, by the springs m and n. This lever operates to rotate the roll b which carries the metallic ring h' from which project the contacts g' on opposite sides of the 90 roll. The periphery of the metallic ring, except at its contacts, is covered by insulating material. When the lever B³ is in its normal position the contacts g' are in engagement with the blades e' and f' on the insulating block B⁵ mounted on the casing B⁴. These blades e' and f' are respectively terminals of the wires 4 and 3. When the lever B³ is in its normal position the circuit between the wires 4 and 3 is completed.

When the lever B³ is moved downwardly by the insertion of a carrier the circuit between the terminals e' and f' is broken. At the same time that the lever moves downwardly it turns the arm c to move the fiber h between the blades e and f on the insulating block B⁶ mounted on the casing B⁴. These blades e and f are respectively terminals of the wires 3 and 7. The metal rivets g in the fiber h complete the circuit between the terminals e and f. After the carrier passes the lever B³ moves to its normal position and turns back the arm c, which interrupts the circuit between the terminals e and f and again establishes the circuit between the terminals e' and f'.

When the lever B³ is moved upwardly on the receipt of a carrier from the opposite end of the tube, the roll b is turned to interrupt the circuit between the terminals e' and f'. As soon as the carrier passes outwardly the lever is returned to its normal position and the circuit between the terminals e' and f' is again completed.

Having thus ascertained the nature of my 125 invention and set forth a construction embodying the same, what I claim as new and desire to secure by Letters Patent of the United States is:

1. In an apparatus of the character de- 130

scribed, a single tube connecting two stations and through which carriers are transmitted, an air pump for said tube, a motor for operating said pump, electric circuits connecting both stations, a circuit maker and breaker in said circuits at each station adapted to be operated by the carriers to start the pump.

5 10 15 20

2. In an apparatus of the character described, a single tube connecting two stations and through which carriers are transmitted, an air pump for said tube, a motor for operating said pump, electric circuits connecting both stations, and an automatic circuit maker and breaker in said circuits at each station and adapted to be operated by the carriers to start or stop the pump.

3. In an apparatus of the character described, a single tube connecting two stations and through which carriers are transmitted, an air pump for said tube, a motor for operating said pump, electric circuits connecting both stations, an automatic circuit maker and breaker in said circuits at each station adapted to be operated by the carriers to start or stop the pump, and means actuated by the electric current passing through said circuits for reversing the direction of the current of air through said tube.

4. In an apparatus of the character described, a single tube connecting two stations and through which carriers are transmitted,

an air pump for said tube, a motor for operating said pump, electric circuits connecting both stations, and an automatic circuit maker and breaker in said circuits at each station and adapted to be operated by the carriers to start the pump.

5. In an apparatus of the character described, a single tube connecting two stations and through which carriers are transmitted, an air pump for said tube; a motor for operating said pump, electric circuits connecting both stations, and an automatic circuit maker and breaker in said circuits at each station and adapted to be operated by the carriers to stop the pump.

6. In an apparatus of the character described, a single tube connecting two stations and through which carriers are transmitted, an air pump for said tube, a motor operating said pump, electric circuits connecting both stations, an automatic circuit maker and breaker in said circuits at each station adapted to be operated by the carriers, and means actuated by the electric current passing through said circuits for reversing the direction of the air current through said tube.

In testimony whereof, I have signed my name to this specification in the presence of two subscribing witnesses, this 20th day of July A. D. 1905.

EDMOND A. FORDYCE.
